REGISTER STAND OR SIMILAR ARTICLE

Morris Lange, University Heights, Ohio

Application October 23, 1948, Serial No. 149,265

Term of patent 7 years

(Cl. D29—23)

To all whom it may concern:

Be it known that I, Morris Lange, a citizen of the United States, residing in the city of University Heights, county of Cuyahoga, and State of Ohio, have invented a new, original, and ornamental Design for a Register Stand or Similar Article, of which the following is a specification, reference being had to the accompanying drawing, forming a part thereof:

surface ornamentation being omitted for convenience of illustration, and

Figure 5 is a fragmentary rear elevational view looking in the direction of the arrows 5—5.

I claim:

The ornamental design for a register stand or similar article, substantially as shown.

MORRIS LANGE.
